TELEPRINTER RECEIVING APPARATUS

Reginald Dennis Salmon, Croydon, Surrey, England, assignor to Creed and Company Limited, Croydon, Surrey, England

Application October 27, 1938, Serial No. 237,183
In Great Britain October 29, 1937

2 Claims. (Cl. 178—25)

This invention relates to teleprinters, in which a movable carriage is moved the space of a printed character after the printing of each character. It has for its object to provide a back spacing mechanism of a simple kind and also one which is adapted particularly to power driven apparatus.

According to this invention the movable carriage is moved in steps through a differential gear mechanism and a function lever for back spacing acts to release a normally stationary part of said differential gear mechanism to move the carriage in the reverse direction for the spaces of one or more characters.

15 The invention will be described as applied to teleprinter apparatus printing in page form in which the movable carriage is moved backwards the space of one character in response to a distinctive signal. The particular form of teleprinter apparatus chosen for illustration is that described in Specification No. 467,352, in which the movable carriage consists of a movable type basket cooperating with stationary selector members, but it is to be understood that the invention is equally applicable to apparatus in which the printing mechanism is stationary and the paper is moved.

20 The nature of the invention will be better understood from the following description of one embodiment thereof taken in conjunction with the accompanying drawing in which:

Fig. 1 is a vertical cross-section of a portion of a teleprinter as shown in Specification No. 467,352, with the invention applied thereto;

35 Fig. 2 is a plan view, and

Fig. 3 is a vertical cross-section on a line at right angles to that of Fig. 1.

Referring to the drawing, the movable type basket of a teleprinter is fixed to a rack 1 driven 40 against the tension of a spring (not shown) by the engagement of the rack 1 with a toothed wheel 2 mounted on a shaft 3 as described in the above mentioned specification. The shaft 3 is driven through a differential gear mechanism described hereinafter by means of a dog clutch, one part 17 of which is secured to a shaft 11 and the other part 15 of which is slidably mounted on a sleeve 12 freely rotatable on the shaft 11. Fixed to the sleeve 12 is a gear wheel 13, which 45 meshes with a worm 14 tending to be rotated through a clutch from a constantly rotating motor driven shaft. The two parts 15 and 17 of the dog clutch by which shaft 11 is clutched to sleeve 12, are normally held in engagement by means 50 of a spring 16. As each character is printed

worm 14 is rotated through a portion of a revolution in known manner and thus rotates shaft 11, which, by means of a differential gearing rotates shaft 3 and gear wheel 2 to step the rack 1 the space of one character. A lever 18 is provided in well known manner to disengage the parts 15 and 17 of the clutch when the carriage return signal is received. This allows a spring (not shown) to move the rack 1 and with it the shafts 3 and 11 until the carriage has returned to the beginning of the line.

5 The differential gear mechanism consists of a gear wheel 4 fixed to the shaft 3, a gear wheel 10 fixed to the shaft 11, and gear wheels 5 and 9. Gear wheel 5 is mounted in a bracket 6 attached to a disc 7 whilst gear wheel 9 is mounted in a bracket 26 attached to a disc 8. Discs 7 and 8 are fixed together and mounted to rotate freely in bearings carried by the aligned ends of shafts 11 and 3. These discs are furnished with teeth around their peripheries, the teeth on the two discs being staggered, and are held stationary by the engagement therewith of a detent 34. Gear wheel 5 meshes with gear wheel 4 and gear wheel 9 which in turn meshes with gear wheel 10.

15 Rotation of the worm 14 in a clockwise direction in Fig. 1 thus causes a movement of the rack 1 downwards through the plane of Fig. 1. It will be observed that owing to the use of this differential gear mechanism the direction of rotation of the gear wheel 13 for letter spacing must be opposite from that of the corresponding gear wheel in the mechanism shown in Specification No. 467,352.

20 For the purpose of effecting back spacing, a function lever 81 is provided. This lever is selected, by a received combination of impulses, through the tilting of a particular combination of the vanes 21, 22, 23, 24 and 25. This lever 81 is pivoted on a rod 82 and urged towards the above mentioned vanes by a spring 83. The selection and actuation of the function lever 81 takes place in a manner similar to that described for other function levers in Specification No. 467,352.

25 A function cam 31 and function bail 27 are provided for this purpose. The function cam 31 is mounted on the same shaft as the worm 14 though shown separately in the drawing for the sake of clearness. It is actuated through a clutch 40 separate from the clutch actuating the worm 14.

30 When the function lever 81 is selected it raises a lever 19 into the path of the function bail 27. The latter is secured to the function actuating lever 28 pivoted at 30 and held so that a roller 35

thereon bears against the function cam 31 by a spring 29. When function lever 81 has been selected therefore and allowed to move to the right in Fig. 1 under the influence of its spring 83, actuation of the function bail 27 by cam 31 draws lever 19 to the right in Fig. 1.

The discs 7 and 8 of the differential gear above referred to are held stationary by the engagement of a forked escapement lever 34 with the teeth on the disc 8. Movement of lever 19 to the right in Fig. 1 moves the forked lever 34 against the spring 35 and allows the discs 7 and 8 to move until the forked lever 34 engages a tooth on the upper disc 7. The carriage of the teleprinter with the rack 1 is being urged to its initial position and release of the discs 7 and 8 allows the rack 1 to rotate the wheel 2 until the carriage has moved back half the space of a character. During the latter half of the revolution of the function cam 31 the lever 19 is free to return to its original position, and the spring 35 is able to restore the forked lever 34 to the position shown in the drawing. The discs 7 and 8 are again released so that rack 1 can move a further half character space.

It will be clear that the normal forward movement of the carriage which is effected after printing of a character is prevented by well known means when the received combination of impulses selects a function lever. It may, however, be arranged that when the back spacing function lever 81 is selected the carriage is stepped for-

ward one space in the same way as if a character had been selected. In that event the teeth on the discs 7 and 8 would be so spaced that the carriage moves backwards one space at each movement of the forked lever 34, that is a total of two spaces.

What is claimed is:

1. A machine telegraph comprising a movable carriage means comprising a differential gear mechanism for moving said carriage in one direction on the receipt of certain signals, a spring tending to move said carriage in the opposite direction and means operative upon the receipt of a separate distinctive signal to release for movement a normally stationary member of said differential gear mechanism to permit movement of said carriage by said spring. 10

2. A machine telegraph comprising a movable carriage, means comprising a differential gear mechanism for moving said carriage in steps in one direction on the receipt of certain signals, said differential gear mechanism comprising an escapement disc normally held stationary, an escapement lever co-operating with said disc, a spring tending to move said carriage in the opposite direction and means operative upon the receipt of a separate distinctive signal to move said escapement lever to permit limited movement of said disc and so permit limited movement of said carriage by said spring. 20 25 30
